UNITED STATES PATENT OFFICE.

HENRY SCHUMACHER, OF BUFFALO, NEW YORK.

ASPHALT CUTTER.

Application filed January 22, 1923. Serial No. 614,095.

To all whom it may concern:

Be it known that I, HENRY SCHUMACHER, a citizen of the United States, residing at Buffalo, in the county of Erie and State of New York, have invented new and useful Improvements in Asphalt Cutters, of which the following is a specification.

This invention relates to an asphalt cutter whereby grooves, channels or furrows may be cut in an asphalt pavement for the purpose of permitting the same to be readily picked up in case a trench is to be formed in the street for laying sewer, gas or water pipes, telephone conduits, or other purposes.

It is the object of this invention to provide a machine for this purpose which is comparatively simple and compact in construction, can be readily adjusted both as to the stroke of the chipping or cutting tool in order to adapt the same to the character of the surface which is being cut and the wear upon the tools, and which can also be easily adjusted for the purpose of propelling the car at various speeds to suit the progress of the cutting, and which can be conveniently controlled by a single operator.

In the accompanying drawings: Figure 1 is a side elevation of my improved asphalt cutter. Figure 2 is a top plan view of the same. Figures 3 and 4 are vertical longitudinal sections of the machine, taken on the correspondingly numbered lines in Fig. 2. Figures 5 and 6 are vertical transverse sections taken on the correspondingly numbered lines in Fig. 2, and looking in the direction of the arrows associated with these lines. Figure 7 is a fragmentary top plan view of the clutch and driving mechanism interposed between the lower intermediate shaft and the longitudinal shaft for propelling the car either forwardly or backwardly at comparatively high speed. Figure 8 is a fragmentary vertical longitudinal section, showing the manner of detachably connecting the hub of one of the cutter tools with one of the helves.

Similar characters of reference indicate corresponding parts throughout the several views.

The frame or body of the asphalt cutter may be variously constructed to support the different working parts of the machine, but as shown in the drawings, the same by preference comprises two longitudinal side pieces 10 and a plurality of cross pieces 11

connecting these side pieces adjacent to the front ends thereof and also at a point adjacent to the central parts thereof. On one side of the body, preferably the left hand side when taken relatively to the direction in which the car moves during the cutting operation, the body is provided with a lateral extension 12 which is designed to permit of cutting a groove in the pavement close to a curb on one side of the street, as will be described later on.

The body or frame of the car may be supported in any suitable or approved manner, but as shown in the drawings, the same is supported at its front end by two traction or driving wheels 13, which are arranged transversely in line and mounted at opposite ends of a driving axle 14, which is journaled in suitable bearings on the main frame, while the rear end is supported by a steering wheel 15 which is journaled in the lower end of a fork 16, the upper end of this fork being secured to an upright steering shaft 17 journaled in an upright bearing on the adjacent part of the main frame, and provided at its upper end with an operating handle 18 which is within convenient reach of the operator's seat 19. This seat, as shown by dotted lines, is mounted on the right hand side of the main frame and preferably faces backwardly, so that the operator while manipulating the various parts of the machine will be able to observe the action of the cutting tools which are mounted on the rear end of the machine and move forwardly as the operation of cutting the groove, furrow or channel progresses.

The mechanism for propelling the car of the asphalt cutter at a rapid speed, so that the same can be quickly transported from one job to another, is preferably constructed as follows:

20 represents a prime mover mounted on the front part of the frame or body, which prime mover by preference is an internal combustion engine, although any suitable motor may be employed, if desired. Motion is transmitted from the driving shaft 21 of this motor to the rear axle 14 by a driving gearing which preferably comprises a chain belt 22 passing around a sprocket wheel 23 on the engine shaft 21, and the sprocket wheel 24, secured to or formed with a sleeve 25 which is mounted on an upper intermediate shaft 26 journaled transversely

and horizontally in suitable bearings on the central upper parts of the side pieces 10, and a chain belt 27 passing around a sprocket wheel 28 on the sleeve 25 and a sprocket wheel 29 which is secured to a lower intermediate shaft 30 journaled in suitable bearings on the central lower parts of the side pieces 10, 10. 31 represents a longitudinal shaft journaled in suitable bearings on the lower rear part of the main frame and provided at its rear end with a bevel gear wheel 32 which meshes with a bevel gear wheel 33 on the driving axle 14, while its front end is provided with a driven bevel gear wheel 34 engaging with two oppositely-facing bevel gear wheels 35, 36, mounted loosely on the lower intermediate shaft 30. Either one of these bevel gear wheels 35, 36 may be connected with a shaft 30, or both may be disconnected therefrom, so as to permit of propelling the car rapidly either forwardly or backwardly, or cutting out the rapid propelling mechanism altogether. This is accomplished by means of a clutch or coupling sleeve 37 splined on the shaft 30 between the bevel gear wheels 35 and 36 and provided at its opposite ends with clutch teeth or shoulders 38, 39, which are adapted to engage with corresponding clutch jaws or teeth 40, 41 on the opposing ends of the gear wheels 35, 36. When the clutch or coupling sleeve 37 is moved into engagement with the clutch faces of the gear wheel 36, as shown in Fig. 7, then the traction wheels will be turned in the direction for moving the car forwardly, while upon moving the clutch sleeve 37 out of engagement from the gear wheel 36 and into engagement with the clutch faces 40 of the gear wheel 35, then the traction wheels will be operated in a direction for moving the car rearwardly, but when the clutch sleeve 37 is shifted into an intermediate position in which the same is disengaged from the clutch faces of both gear wheels 35 and 36, then no power is transmitted from the prime mover to the traction wheels and the quick propelling mechanism for the car is rendered inoperative. The clutch sleeve 37 may be shifted in any suitable way, for instance, by means of a fork 42 engaging with this sleeve and mounted on the lower end of an upright shaft 43 which is journaled in suitable bearings on the main frame and provided at its upper end with a hand lever 44 which is within convenient reach of the operator's seat 19. This handle is provided with a catch 45 which may be engaged with a locking segment 46 on the adjacent part of the main frame for holding the quick-propelling mechanism either in its inoperative position or in a position in which the car is propelling forwardly or backwardly at a rapid speed.

65 For the purpose of propelling the car

slowly in a forward direction while the cutting of the asphalt surface is being effected, the following means are provided:

47 represents a ratchet wheel connected with the inner side of each of the traction wheels 13, so as to turn therewith. Adjacent to each of these ratchet wheels, a ratchet lever 48 is mounted to turn on the axle 14 and provided with a feed pawl 49 which is adapted to engage with the adjacent ratchet wheel 47 during the forward throw of the lever 48, but to slide idly over this ratchet wheel during the backward throw of this lever. The oscillating movement of each of these ratchet levers is effected by means of an intermediate operating rock lever 50 arranged lengthwise adjacent to the inner side of each of the side pieces 10 of the main frame and connected at its front end by means of a link 51 with the free end of the ratchet lever 48, while its rear end is provided with two longitudinal parallel guide bars 52, 53, forming part of a yoke which bars are engaged on their opposing sides by a rotary eccentric 54. The two eccentrics 54 associated with the respective rock levers 50 are mounted on a horizontal shaft 55 which is journaled transversely in bearings on the upper central part of the main frame. This shaft is rotated by motion derived from the engine shaft 21 through the medium of an intermediate driving mechanism, which in its preferred form comprises a shaft 26 and the parts associated therewith, and driving gear pinions 56 arranged at opposite ends of the shaft 26 and meshing with gear wheels 57 arranged at opposite ends of the shaft 55. The sleeve 25 turns loosely on the shaft 26 when the high-speed propelling mechanism is in operation, so that the slow-speed propelling mechanism will not be operated. When it is desired to cut out the high-speed propelling mechanism and substitute therefor the slow-speed propelling mechanism, then the clutch sleeve 37 is moved into a position intermediate of the gear wheels 35 and 36 and the shaft 26 is coupled with the sprocket wheel 24, so that motion from the engine will now be transmitted to the slow-speed propelling mechanism. In its preferred construction, this mechanism consists of a clutch having a clutch rim 58 secured to the side of the sprocket wheel 24, and a clutch sleeve 59 splined on the shaft 26 and provided with a clutch jaw or cone 60 adapted to be engaged with or disengaged from the clutch rim 58. As shown in Fig. 5, the clutch members 59 and 60 are engaged, whereby motion is transmitted from the engine to the slow-speed propelling mechanism, while upon disengaging these clutch members the slow speed mechanism will be rendered inoperative. These clutch members may be engaged and disengaged by

means of a shifting fork 61 engaging with a clutch sleeve 59 and secured to the lower end of an upright operating rock shaft 62 journalled on the frame and provided at its 5 upper end with a hand lever 63 arranged adjacent to the operator's seat 19 and provided with a locking dog 64 adapted to engage with a locking segment 65 for holding the clutch of the slow-speed driving 10 mechanism either in its operative or inoperative position.

As the shaft 55 is rotated by power derived from the engine, its cams or eccentrics 54 raise and lower the rear ends of the rock 15 shafts 50, thereby causing the front ends of the same to alternately move the ratchet levers 48 forwardly and backwardly and thereby advance the car at a slow rate as the cutting of the groove or furrow in the 20 asphalt pavement progresses.

Means are provided for varying the length of the steps of the forward movement of the car in accordance with the character of the pavement which is being cut, it being 25 possible to cut the pavement more rapidly when the same is thin or when the weather is warm than when the pavement is thick or the weather is cold, and the rate of cutting being also determined by the degree of hardness of material. To permit of varying the 30 rate of advance of the slow-propelling mechanism in accordance with different conditions, means are provided for varying the fulcrum of the operating levers 50, so that

35 the front and rear arms thereof may be either shortened or lengthened relatively to the operating cam 54 and the ratchet levers 48. In the preferred form of this adjusting mechanism, each of the operating levers 50 40 is provided on its underside with a longitudinal gear rack 66 which is arranged adjacent to a lower gear rack 67 arranged lengthwise on the adjacent part of the respective side piece 10 of the main frame, a 45 transverse shaft 68 provided at each end with an outer gear wheel 69 engaging with the lower gear rack 67 and an inner gear wheel 70 meshing with the adjacent upper gear rack 66. Upon turning the shaft 68

50 in one direction or the other, the outer gear wheel 67 will roll back and forth on the lower gear rack 67 in a direction lengthwise of the levers 50 and thereby cause the inner gear wheels 70, by engagement with the upper gear rack 66, to move the rock levers 50 55 bodily either forwardly or backwardly, lengthwise of the frame. Upon moving the rock levers backwardly, the distance between the fulcrum of these levers, which is represented by the shaft 68 and the axes of the 60 rotary cams 54 is shortened, thereby increasing the throw of these levers, so far as the effect of the same on the ratchet levers 48 is concerned, while upon turning the shaft 68 in the direction for causing the outer

gear wheels 69 to roll forwardly on the lower gear rack 67, the inner gear wheels 70 will cause the upper gear racks 66 to move forwardly and thereby lengthen the distance from the fulcrum of the rock levers 50 70 which is represented by the shaft 68 to the axes of the operating cams or eccentrics 54, whereby the strokes of these levers 50, so far as their effect upon the ratchet levers 48 is concerned, is reduced. It therefore follows 75 that by moving the shaft 68 either forwardly or backwardly, the rear arms of the rock levers 50 may be either shortened or lengthened, so far as the effective purpose of the same is concerned, and thereby permit of 80 adjusting the length of the steps of the forward slot mechanism accordingly. In order to hold these parts in their proper assembled position, each of the rock levers 50 is embraced by a yoke 71, the lower end of which 85 is mounted on the shaft 68 while its upper part is provided with anti-friction rollers 72 adapted to move lengthwise over the upper side of the respective feed lever 50, as best shown in Figs. 4 and 5. The shaft 90 68 is confined against vertical displacement but free to move lengthwise of the machine by engaging opposite ends thereof with longitudinal guide ways 73 arranged on the inner sides of the longitudinal members 10 95 of the main frame.

Rotary motion may be imparted to the shaft 68 for moving the gear wheels 69 and 70 either forwardly or backwardly by various means, for instance, this may be accomplished by means of an adjusting gear wheel 74 secured to the shaft 68 and an adjusting lever 75 mounted loosely on this shaft and provided with a hand-operated dog 76 which may be engaged with successive teeth of the adjusting gear wheel 74, for the purpose of turning the shaft 68 either in one direction or the other and effecting the adjustment of the slow-speed propelling mechanism accordingly.

The mechanism for cutting or chipping a groove, furrow or channel in the surface of the pavement comprises two vertically-swinging helvles 77 which are mounted on the rear part of the machine and diverge from their rear ends toward their front ends. The cutting bits or tools 78 may be mounted on the rear ends of these helvles in any suitable manner, but this mounting is preferably so effected that the bits or tools 110 may be readily removed from the helvles for the purpose of sharpening these tools or replacing the same with new ones when worn out. For this purpose, a holder is provided for each of the tools or bits which comprises 115 a tubular hub 79 having a tapering bore or opening 80 which engages with the correspondingly tapering shank 81 at the rear end of one of the helvles, this hub being retained 120 on its shank by means of a screw member 125

82 having preferably the form of a nut mounted on the rear end of the shank and engaging with the rear side of the hub of the holder, as best shown in Fig. 8. On its underside the hub of the holder is provided with a downwardly-projecting arm 83 which is provided on one side with a rectangular rabbet 84 in which the upper end of the respective tool or bit 78 is secured by means 10 of bolts 85, as shown, or other suitable means. By detaching the bolts 85, a new bit may be substituted for a worn one on the holder, and by removing the nut 82, the holder may be removed from the helve 77 to 15 permit of sharpening the bit. This manner of connecting the bit with the helve is very strong and reliably holds the bit in place on the helve, as well as permitting the latter to be conveniently renewed or removed, 20 when necessary. A rocking or vertically swinging motion is imparted to the helvess by means which are constructed as follows:

25 86 represents a supporting rod mounted horizontally and transversely on the upper front part of the side pieces of the main frame. Upon this rod adjacent to opposite sides of the frame are mounted the hubs 87 of two vertically swinging rock levers 30 each of which has a front arm 88 operatively connected with the prime mover and a rear arm 89 upon which the front end of one of the helvess 77 is mounted. The connection between this helve and the rock arm 89 35 is preferably of a detachable character, for which purpose this arm is divided lengthwise into lower and upper sections 90, 91, which receive between them the front end of the helve and grip the latter by means 40 of bolts 92 which connect the sections 90, 91 forming a socket for this helve. In order to prevent the helve from turning in its socket, the opposing surfaces of the socket sections 90, 91 are made of flat sided 45 or angular form and the front end of the helve 93 which engages with the socket is made of corresponding form, as shown in Fig. 2, thereby preventing the helve from turning and also maintaining the tool 50 mounted at the rear end thereof in its proper position.

55 The lowering of each helve is preferably effected by a spring, for which purpose a spring 94 of volute form is employed the inner end of which is connected with a relatively fixed part of the frame while its outer end is connected with one of the helvess. In the preferred construction, each of the springs 94 has its inner end constructed in 60 the form of an angular hook 95 which engages with the periphery of a supporting bar 96 which is also of angular form in cross section, as best shown in Fig. 3, whereby these parts are interlocked with each other. 65 The outer end of each volute spring 94 is its upper part passes through the ball 105

connected with the respective helve by means which are capable of sliding on the latter, these means comprising a yoke 97 embracing this helve and connected at its lower end with the outer end of the spring 94, while its upper part is provided with a roller 98 adapted to run lengthwise on the upper side of this helve, as shown in Figs. 1, 2 and 3. When the helve is raised, the tension of the spring 94 is increased, so that when the helve is released, resilience of the spring will cause the helve to be pulled downwardly quickly and deliver a blow of its cutter upon the surface of the asphalt. During this action of the spring, the yoke 97 moves backwardly and forwardly on the helve the requisite extent without causing any cramping action between these parts and thus insuring free movement of the helve. In order to permit of varying the tension upon each of the springs 94, so as to compensate for any weakening of the same or to adapt the same to the character of the asphalt surface which is being cut, means are provided to permit of turning the shaft 96 90 either forwardly or backwardly and holding it in its adjusted position. For this purpose, each of the shafts 96 is journaled at its opposite ends in suitable bearings on the main frame, and a ratchet locking wheel 99 95 is provided which is engaged by a locking dog 100 held in engagement therewith by means of a spring 101 which connects this dog with an adjacent part of the main frame, as best shown in Figs. 1 and 4. When it is 100 desired to vary the tension of the spring 94, the companion dog 100 is first disengaged from the respective ratchet wheel 99 and then the shaft 96 carrying this ratchet wheel and connected with the inner end of the 105 spring 94 may be turned in either direction by applying a wrench to the angular or flattened sides of the same, whereby the shaft may be turned in one direction or the other for either increasing or decreasing its tension and then the spring may be maintained in this condition by re-engaging the dog 100 with the respective ratchet wheel.

110 The raising of the helvess preparatory to delivering blows of its cutters upon the asphalt pavement is effected by means which are interposed between the shaft 55 and the rear arm 88 of each of the helve operating levers. In its preferred construction, these means for accomplishing this purpose are 115 constructed as follows:

120 102 represents a vertically-movable carriage which is guided in a way 103 on the lower part of the main frame and which is connected on its upper rear side with the rear arm 88 of the respective helve lever by means of an upright link 104 pivotally connected at its lower end with the upper rear 125 part of the respective carriage 102, while the outer end of the link 104 passes through the ball 105

seated in a socket 106 on the rear arm 88, a screw nut 107 arranged at the upper end of the rod 104 and a spring 108 surrounding the upper part of the rod 104 and interposed between the underside of the screw nut 107 and the upper side of the ball 105. The depression of the carriage 102 for the purpose of raising the helve is effected by means of a rotary cam which consists of a body 109 secured to the shaft 55 and provided with a rolling bearing surface consisting of a plurality of rollers 110 journaled on the body 109 and adapted to engage with the upper end of the respective carriage 102. As the cam 109, 110 depresses the carriage 102, this motion is transmitted by means of the link 104 and associated parts to the rear arm 88 of the helve lever, whereby this arm is depressed and its front arm elevated, together with the helve. As the came 109, 110 clears the upper end of the carriage 102, the spring 94 by its resilience quickly draws the helve downwardly and delivers a sharp plow of the tool against the asphalt surface which is being cut.

In order to permit the carriage 102 to slide upwardly in its way 103 without liability of binding, notwithstanding that the link 104 is connected therewith adjacent to its upper rear part, a compensating spring 111 is employed which connects the lower front part 112 of the carriage with an adjacent part of the main frame, as best shown in Fig. 3. By this means, the lower end of the carriage will be constantly drawn forwardly at the same time that the carriage is moved upwardly, and thus offset any tendency to tip this carriage forwardly at its upper end which otherwise would cause binding of the same in the guideway 103 and thus interfere with the free downward movement of the respective helve.

By interposing a spring 108 between the screw nut 107 and the ball 105, the movement of the carriage 102 is transmitted to the helve lever 88, 89 with a cushioning effect and thereby prevent undue jarring of the machine and saving wear on the same. By backing the screw nut 107 more or less, the distance between the carriage and the arm 88 may be lengthened to lower the helve and compensate for the wear on the tool or blade of the cutter and still retain the carriage in the same relation to the cam 109, 110. The ball 105 is preferably held against turning by providing its opposite ends with trunnions 113 engaging with seats 114 on opposite sides of the socket 106.

When the asphalt cutter is to be transported considerable distances from one job to another, or when taking the same back and forth between the store house and a particular job, the helves are both elevated into their inoperative position for which purpose a lifting bar 115 is employed, which

is arranged horizontally and lengthwise underneath the outer ends of both tension springs 94, so that upon raising and lowering this lifting bar both helves may be either raised into their inoperative position or lowered into their operative position. This lifting bar is mounted on its opposite ends with vertically-swinging lifting arms 116 which are secured to opposite ends of a rock shaft 117 journaled transversely on the main frame. This rock shaft may be manipulated by the operator while occupying the seat 19 by means of a shifting lever 118 which is of elbow-form and pivoted on the outer side of the right hand frame member 10, the lower arm of this lever being connected by means of a link 119 with an intermediate rock arm 120 secured to the adjacent end of the lifting rock shaft 117, and this lever being held in its various positions by means of a locking dog 121 mounted thereon and engaging with a locking segment 122 on the adjacent part of the main frame.

While the machine is being transported or propelled at a high speed and the helves are elevated into their operative position, the slow-speed pawls 49 are also preferably disengaged from the ratchet wheels 47, so as to not interfere with either the free backward as well as the forward movement of the car at this time. For this purpose, a rock shaft 125 is journaled transversely in the upper front part of the frame and provided with two lifting arms 126, each of which is connected by means of a chain 127 or other flexible member with a lifting arm 128 formed on the respective propelling pawl 49, as shown in Fig. 4. Upon turning this shaft 125 in one direction, the two pawls 49 will be disengaged from the ratchet wheels 47, but when turning this shaft in the opposite direction, these pawls will be permitted to re-engage with their respective ratchet wheels. In order to permit of raising the helves into their inoperative position and simultaneously disengaging the slow-feed pawls 49 from the ratchet wheels 47 by manipulating a single member, a connection is established between the ratchet operating rock shaft 125 and the lever 118, which in its preferred form consists of a shifting arm 129 which is secured to the outer end of the shaft 126 and a connecting rod 130 which connects this arm 129 with the upper arm of the elbow-lever 118, as shown in Fig. 1. By this means, the helves and the slow-motion propelling mechanism may be simultaneously rendered operative and inoperative.

As a whole, this asphalt cutter is very strong and durable, its several parts, though compact, are easily accessible for adjustment, inspection and repairs, and the same can be readily manipulated with a minimum

amount of care for cutting asphalt expeditiously and effectively under different conditions and various compositions of material.

5. I claim as my invention:

1. An asphalt cutter comprising a horizontal rock shaft, a helve mounted on said shaft and carrying a cutting tool, means for elevating said helve, and means for depressing

10. said helve comprising a volute spring having its inner end connected with a relatively fixed part and a yoke slidable lengthwise on the helve and having its lower part connected with the outer end of said spring

15. and provided on its upper part with a roller running on the upper side of said helve.

2. An asphalt cutter comprising a horizontal rock shaft, a helve mounted on said shaft and carrying a cutting tool, means for

20. elevating said helve, and means for depressing said helve comprising a volute spring having its inner end constructed in the form of an angular hook, a shaft mounted on a relatively stationary part and having an

25. angular part which engages with said hook, and means for rotatably adjusting said shaft, comprising a ratchet wheel mounted on said shaft and a locking dog mounted on a stationary part and engaging with said

30. ratchet wheel.

3. An asphalt cutter comprising a vertically swinging lever, a helve mounted on one arm of said lever, a vertically movable carriage connected on one side with one arm 35. of said lever, a rotary cam engaging with the top of said carriage for depressing the same and raising said helve, and a spring connected with the opposite side of said carriage and adapted to prevent the same

40. from binding during its rising movement.

4. An asphalt cutter comprising a vertically-swinging lever, a helve mounted on one arm of said lever, a vertically reciprocating carriage, and means for adjustably connecting 45. said carriage with the other arm of said lever comprising a ball journaled on the last mentioned arm of said lever, a connecting rod passing through said ball and connected at its lower end with said carriage, 50. an adjusting screw nut arranged on the upper end of said rod, and a spring interposed between said ball and screw nut.

5. An asphalt cutter comprising a vertically swinging helve having a cutting tool, 55. means for propelling said asphalt cutter, means for raising said helve into an inoperative position, and means for rendering said propelling means inoperative when the helve is raised and rendering the same operative when the helve is lowered.

6. An asphalt cutter comprising a plurality of vertically swinging helves each of which is provided with a cutter, means for actuating said helves, and means for elevating the same into an inoperative position

comprising a lifting rod arranged transversely below said helves, a rock shaft provided with arms carrying said rod, an intermediate arm arranged on said rock shaft, an operating lever having a handle on one 70 of its arms and having its other arm connected with said intermediate arm, means for propelling said asphalt cutter comprising a driving wheel, a ratchet wheel connected with the driving wheel, a ratchet lever, a pawl mounted on the ratchet lever and engaging the ratchet wheel, and means for rendering said propelling means inoperative when the helve is raised and rendering the same operative when the helve is 80 lowered.

7. An asphalt cutter comprising a plurality of vertically swinging helves each of which is provided with a cutter, means for actuating said helves, and means for elevating the same into an inoperative position comprising a lifting rod arranged transversely below said helves, a rock shaft provided with arms carrying said rod, an intermediate arm arranged on said rock shaft, an operating lever having a handle on one 85 of its arms and having its other arm connected with said intermediate arm, means for propelling said asphalt cutter comprising a driving wheel, a ratchet wheel connected with the driving wheel, a ratchet lever, a pawl mounted on the ratchet lever and engaging the ratchet wheel, and means for rendering said propelling means inoperative when the helve is raised and rendering the same operative when the helve is lowered comprising a rock shaft having an inner arm 90 connected with said pawl and an outer arm connected with said operating lever.

8. An asphalt cutter comprising a frame, a traction wheel supporting said frame, a cutting tool mounted on said frame, and means for propelling said frame comprising a ratchet wheel connected with said traction wheel, a ratchet lever having a pawl engaging said ratchet wheel, a rock lever connected at one end with said ratchet lever, and provided at its opposite end with a yoke, a rotary cam engaging with said yoke, and means for adjusting the fulcrum of said lever, including gear racks arranged on adjacent parts of the frame and lever and gear wheels engaging with said gear racks.

9. An asphalt cutter comprising a frame, cutting tools mounted on the frame, traction wheels supporting said frame, means for turning said traction wheels comprising ratchet wheels turning with said traction wheels, ratchet levers provided with pawls engaging with said ratchet wheels, propelling rock levers each having one end connected with one of said ratchet levers and provided at its other end with a yoke, rotary cams engaging with said yokes, gear racks arranged on each lever and the adjacent 100

110

115

120

125

130

part of the pairs of shifting gear wheels, one member of each pair engaging with the gear rack of one of said levers and the other member of a pair engaging the companion gear rack on the frame, an adjusting shaft connecting said shifting gear wheels, guide-ways on the frame for the ends of said adjusting shaft, yokes each embracing one of said levers and pivotally connected with one end of said adjusting shaft, an adjusting gear wheel on said shaft, and an adjusting lever mounted on said shaft and provided with a dog engaging said adjusting gear wheel. 10

HENRY SCHUMACHER.
